CESARE PICCARDO, OF GENOA, ITALY

APPARATUS FOR THE CONTINUOUS AUTOMATIC DISCHARGE OF MUD FROM STEAM BOILERS AND HEATERS OF LIQUIDS

Application filed August 21, 1928, Serial No. 301,036, and in Germany February 13, 1928.

The invention refers to an apparatus for the continuous and automatic discharge of mud from steam boilers in which it is essential that a mud separator is thus connected with the water space of the boiler by means of circulating conduits supplied with automatic valves in which the circulation takes place by the difference of temperature, so that these valves by the simple opening and closing of the discharge cock of the separator are automatically placed in the open or closed position.

The discharge of water from the boiler takes place in a zone of the highest concentration of mud while the connection with the boiler for the return branch takes place in a zone in which the water is not intensively heated.

The circulation of the water between the boiler and the separator takes place owing to the difference of temperature in the manner that a part of the conduit is conveniently cooled.

The particular construction of the separator also constitutes a further object of the invention.

The invention is illustrated in a form of execution in the drawing and

Figures 1 and 2 show the device in connection with a tube boiler and with a flue boiler respectively.

Figure 3 is a detail of the mud separator. In these figures, 1 is the boiler, 2 is the mud separator so arranged with reference to the boiler as to be situated below the water level. In the conduits leading from the connections 3 and 4 on the boiler to the separator are arranged non-return valves 5 and 6. The conduits between the boiler and the separator are insulated with the exception of such a piece of the conduit so as to produce, on account of the obtained difference of temperature, the required circulation. In the illustrated form of execution the noninsulated conduit is the vertical piping arranged to the right of the separator, as shown in Figs. 1 and 2. This piping may eventually be supplied with ribs or shaped as a coil so as to increase its cooling surface. 7 and 8 are air discharge and testing cocks and 9 is the dis-

charge cock of the separator. 10 and 11 are flanged tubular pieces inserted in the conduits before and behind the separator; each one carries two diametrically opposite inspection glasses, across which, from the outside, the circulating water can be controlled.

In the cylindrical receptacle 2 is axially secured upon the cover 12 the tubular piece 13 which coaxially encloses an inner tubular piece 14; the latter connects in the interior of the receptacle 2 with the descending tube 15 and towards the top is connected with a cup 16 in which is stored a chemical reagent or a scale disincrustant solvent. The conduit admitting the boiler water to the separator is connected with the tubular piece 14, the conduit discharging the boiler water from the separator is connected with the tubular piece 13. 17 is a regulating cock for the admission of the chemical reagent within the separator and 18 is a threaded plug with handlever in order to fill the cup 16 with said reagent or scale solvent. Upon the descending pipe 15 are arranged two groups of superposed frustums of cones 19 and 20, of which the inner group 19 is immediately fastened upon the descending tube and the outer group 20 upon the inner group. By this arrangement between an inner and an outer cone is produced an annular coaxial passage. 21 and 22 are two threaded shafts which carry hand wheels and which can be adjusted against the valves 5 and 6 so as to open the valve passages. 23 indicates a cock provided on the cup 16 for the discharge and the control of the contents of this cup.

The device works as follows:

The muddy boiler water circulates in the direction of the arrows. The speed of this circulation is not sufficient to close the two non-return valves 5 and 6 which remain completely opened on account of their weights. The speed of the circulation can be regulated by adjusting the valves 3 and 4 as well as the size of the ribbed cooling surface. The water entering the tubular piece 14 rises above the liquid in the cup due to the difference in density and temperature. The adjustment of the cock 17 establishes the time in which the contents of the cup 16 must be displaced by

the boiler water, that is to say in which same have to flow in the separator. The application of the cup 16 upon the separator tends to favor the partial precipitation of the salts within the separator and in this way to favor and facilitate the separation of the mud from the boiler water.

The hot muddy water issuing from the lower end of the descending tube 15 with diminished speed finds its way immediately towards the upper part of the separator and reaches by the shortest path the discharge. The muddy boiler water describes in its ascent a zig zag path and traverses in this way the annular grooves between the two groups of frustums of cones, the mud during this passage, on account of the successive deviation (see arrows) getting separated by the centrifugal force, from the water and flowing on account of its inertia across the quiet zones in the intervals between the outer frustums of cones within the annular space along the shell of the separator. From this annular space the mud is easily collected at the bottom of the receptacle on account of the descending motion of the water cooled by the contact with the shell, the descending water along the shell favoring the attraction of the mud from the quiet zones between the frustums of cones.

The water thus liberated from the mud returns to the boiler. From time to time the mud collected in the separator is conducted towards the outside by the discharge cock 9. In opening this cock during the working of the device is immediately produced by the decreased pressure in the separator 2 an increased speed in one circulating pipe which displaces the non-return valve 5 and an increased speed of the reversed flow in the other circulating pipe to displace the non-return valve 6 closing both of them so that the discharge of the separator is not influenced by the pressure of the boiler. As soon as the discharge cock 9 is again closed pressure is again produced in the separator, this through the imperfect tightness of the valves 5 and 6 caused by a slight cut made in the valve or by an insufficient grinding. If this pressure has again reached the value of the pressure of the boiler the non-return valves are again in equilibrium and open again by their own weight, so that the normal circulation is again established. For washing out the separator the discharge cock 9 will be opened as well as the valves 5 and 6 by displacing the valve rods 21 and 22.

It is obvious that the device can just as well be adapted for liquid heaters of various types.

Having now particularly described and ascertained the nature of my said invention and in what manner the same is to be performed, I declare that what I claim is:—

65 1. Apparatus for the continuous discharge

of mud from steam boilers and heaters of liquid comprising a boiler, a separator including a discharge cock, connections between the boiler and the separator, means for regulating the speed of the circulating water across the separator and valves arranged on the pipe connections between the boiler and the separator, which are automatically brought to the open or closed position by closing or opening the discharge cock of the separator so as to allow the discharge of the separator at the outside pressure.

2. Apparatus of the type specified comprising a boiler, a separator including a discharge cock, connections between the boiler and the separator, means for regulating the speed of the circulating water, non-return valves arranged on the connections between the boiler and the separator which close from the bottom, and present a piping which connects from the bottom so as to eliminate spaces in the valve body for the collection of mud and to obtain that the valve opening takes place by its own weight, the non-return valves being brought to the open or closed position by closing or opening the discharge cock of the separator.

3. Apparatus of the type specified comprising a boiler, a separator, connections between the boiler and the separator, the separator including a receptacle, a discharge cock at the bottom thereof, a descending central pipe and two coaxial groups of frustums of cones within the receptacle and alternately arranged with respect to each other so as to provide an annular zigzag like passage for the ascension of muddy water in the central part of the receptacle and the separation of the mud from the water, non-return valves arranged on the connections between the boiler and the separator, and adapted to be moved to the open or closed position by closing or opening the discharge cock of the separator.

4. Apparatus of the type specified comprising a boiler, a separator, connections between the boiler and the separator, the separator including a receptacle, a discharge cock at the bottom of the receptacle, a descending central pipe, two coaxial groups of frustums of cones within the receptacle and alternately arranged with respect to each other so as to provide an annular zigzag like passage for the ascension of the muddy water, coming from the descending pipe, and the separation of the mud from the water, means for regulating the speed of the circulating water across the separator, non-return valves arranged on the connections between the boiler and the separator and adapted to be brought to the open or closed position by closing or opening the discharge cock of the separator, inspection glasses arranged on the connecting pipes between the boiler and separator and a chemical scale disincrustant

solvent storing cup arranged above and in connection with the separator.

5. In a hot water piping of a heater of liquid, a mud separator comprising a receptacle, a discharge cock at the bottom thereof, a descending central pipe and two coaxial groups of frustums of cones within the receptacle and alternatively arranged with respect to each other so as to provide an annular zigzag passage for the ascension of muddy water in the central part of the receptacle, further large intervals between the frustums of cones of the outer group for the separation of the mud and an annular space between the outer edges of the outer group of frustums of cones and the shell of the receptacle for the collection and the deposition of the mud.

10 6. Apparatus of the type specified comprising a boiler, a separator, connections between the boiler and the separator, the separator including a receptacle, a discharge cock at the bottom thereof, a descending central pipe and two coaxial groups of frustums of cones within the receptacle and alternatively arranged with respect to each other so as to provide an annular zigzag like passage for the ascension of muddy water in the central part of the receptacle, and further large intervals between the frustums of cones of the outer group for the separation of the mud and an annular space between the outer edges of the outer group of frustums of cones and the shell of the receptacle for the collection and the deposition of the mud, non-return valves arranged on the connections between the boiler and the separator, and adapted to be moved to the open or closed position by closing or opening the discharge cock of the separator.

15 7. Apparatus of the type specified comprising a boiler, a separator, connections between the boiler and the separator, the separator including a receptacle, a discharge cock at the bottom of the receptacle, a descending central pipe, two coaxial groups of frustums of cones within the receptacle and alternately arranged with respect to each other so as to provide an annular zigzag like passage for the ascension of the muddy water in the central part of the receptacle and further intervals between the frustums of cones of the outer group for the separation of the mud and an annular space between the outer edges of the outer groups of frustums of cones and the shell of the receptacle for the collection and the deposition, (decantation) of the mud, means for regulating the speed of the circulating water across the separator, non-return valves arranged on the connections between the boiler and the separator and adapted to be brought to the open or closed position by closing or opening the discharge cock of the separator, inspection glasses arranged on the connecting pipes between the boiler and separator, and a chem-

ical scale disincerustant solvent storing cup arranged above and in connection with the separator.

8. In a hot water piping of a heater of liquid, a mud separator comprising a receptacle, a mud discharge cock at the bottom thereof, a descending central valve controlled pipe connected to the hot water inlet, an inner group of rather short frustums of cones tightly fitted and arranged coaxially to the descending tube, an outer group of frustums of cones also coaxially arranged with respect to the descending tube but having their inner edges spaced apart from this tube and each projecting between the outer edges of the corresponding pair of inner cones and extending with their outer and base edges a short distance apart from the shell of the receptacle, the two groups of frustums of cones forming between them an annular zigzag like passage for the ascension of the muddy water in the proximity of the descending tube formed; and a valve controlled discharge of clean hot water from the separator arranged in communication with said zigzag passage.

20 In testimony whereof I have signed my name to this specification.

CESARE PICCARDO.
